MARION E. PLAYFORD, OF WAKELEE, MICHIGAN, ASSIGNOR OF ONE-FOURTH TO FRENCH H. ALEXANDER AND ONE-FOURTH TO CHESTER A. PLAYFORD, BOTH OF CASSOPOLIS, MICHIGAN.

ROTARY PLOW.

1,082,357.

Specification of Letters Patent.

Patented Dec. 23, 1913.

Application filed April 19, 1911. Serial No. 622,094.

To all whom it may concern:

Be it known that I, MARION E. PLAYFORD, a citizen of the United States, and a resident of Wakelee, in the county of Cass and State of Michigan, have invented a new and Improved Rotary Plow, of which the following is a full, clear, and exact description.

My invention relates to plows, my more particular purpose being to provide a so-called "rotary plow" having spiral cutting blades so formed and fitted as to be specially adaptable for use in a motor plow.

My invention further comprehends certain improvements of a general nature related to plows of this type and tending to improve the general efficiency of the plow.

Reference is to be had to the accompanying drawings forming a part of this specification in which like characters of reference indicate corresponding parts in all the views, and in which—

Figure 1 is a side elevation partly in section of this improvement. Fig. 2 is an elevation showing one of the cutting blades and the manner in which it is mounted; and Fig. 3 is a plan view.

Referring to the drawing A is the plow and B a shaft adapted to be rotated and upon which the plow is mounted. The plow 30 comprises a spider a having a hub a² provided with oppositely projecting arms a³, spokes b, shoes c, and blades d. The spider is secured to the shaft B by a set screw a⁴ and the arms of the spider are provided with grooves a⁵ in which the spokes b are secured by bolts b². The shoes c are substantially L-shaped and the blades d are secured approximately at their center of length in the angle formed by the members 40 of the shoes. As shown in the drawing the shoes and blades are secured to the spokes by the same bolts c², but separate fastening means may be employed for said parts if desired.

Each cutting blade d is curved into arcuate form in the general direction of its length and is tilted slightly by the shoe c, so that the cutting edge of the blade is displaced angularly from the general plane in 50 which the spoke rotates; that is to say, the

cutting edge of the blade is inclined to the plane of rotation of the spoke.

In practice a plurality of the plows will generally be mounted upon the shaft, and the spider of each plow will be so secured to the shaft as to make a slight angular displacement relatively to the next preceding one, so that the several successive spiders bear more or less approximation to a spiral.

By constructing the plow as above described, a very simple, cheap and efficient plow is produced, and one which can be readily assembled or taken apart for transportation or storage.

Having thus described my invention what I claim as new and desire to secure by Letters Patent is:—

1. A plow, comprising a revoluble shaft, a spider provided with a hub fitting on said shaft, means for securing the spider to the shaft, spokes mounted upon the spider and extending in diametrically opposite directions, substantially L-shaped shoes mounted upon the outer ends of the spokes, and cutting blades secured approximately at their center of length to the shoes, said blades being curved in the direction of their length and having their cutting edges inclined relatively to the plane of rotation of the spokes.

2. A revoluble plow member, comprising a spider provided with a hub and spokes projecting from diametrically opposite sides of the hub, L-shaped shoes secured to the outer ends of the spokes with one member projecting in the direction of the length of the hub, elongated cutting blades curved in direction of their length, and means for securing said blades approximately at their center of length in the angle formed by the members of the shoes, with their cutting edges inclined to the plane of rotation of said spokes.

In testimony whereof I have signed my name to this specification in the presence of two subscribing witnesses.

MARION E. PLAYFORD.
